UNITED STATES PATENT OFFICE.

PAUL SCHWERIN, OF NEW YORK, N. Y., ASSIGNOR TO WESTERN ELECTRIC COMPANY, INCORPORATED, OF NEW YORK, N. Y., A CORPORATION OF NEW YORK.

ELECTRIC DISCHARGE DEVICE.

Application filed December 30, 1921. Serial No. 525,985.

This application relates to electric discharge devices and more especially to the structural arrangement and design of the electrodes.

- 5 In certain types of electron discharge devices the cathode comprises a filament of extremely small diameter which is supported between the ends of leading-in wires to which the ends of the filament are welded. 60
 10 It has been found that in several instances the filament has broken at the point of welding. The cause of this is not known but may be that, due to the fineness of the filament, when it is heated to a molten condition during the welding operation some of the metal flows away from the welding point, thereby 65 weakening the filament by reducing the cross-sectional area adjacent this point.

It is one object of this invention to overcome this difficulty and thereby increase the life of electron discharge devices using filaments of extremely small diameter.

This object may be attained by mechanically attaching to either end of the filament 75 a metallic member having a much larger effective diameter than that of the filament and then welding the members to the lead wires. These members are of sufficient size so that in spite of any weakening of them 80 that may take place during the welding operation they are stronger than the filament.

An additional object of the invention is the maintaining of the various electrodes in the proper relation to each other, and particularly in electron discharge devices comprising a control electrode or grid between the anode and cathode in an evacuated vessel.

This object is attained in the preferred 40 form of the invention by extending two metallic supporting members from the press of the enclosing vessel beyond the boundaries of the electrodes and connecting their ends by insulating material. The 45 three electrodes are supported respectively by the two metallic members and the insulating material.

Other objects and novel features of the invention will be apparent from the following specification and accompanying drawing wherein the figure is an elevation of an electron discharge device embodying the invention.

The bulb 10 is provided with a base 11 and 55 the lower end of the bulb is sealed around

the metallic members 12, 13, 14 and 15 which serve as leading-in wires for the electrodes. The members 12 and 15 extend nearly to the end of the bulb and carry at their free ends the insulating member 16 which is preferably a rod of glass having the ends of the members 12 and 15 sealed therein. A spring 17 is welded to a flattened portion of the member 12 near the outer end thereof and extends at right angles therefrom toward the member 15. Suspended from the free end of the spring 17 and the member 13 is the cathode 18 which comprises a filament, the ends of which have been inserted in sleeves 19 and 19^a which are flattened down 70 against the filament to form a mechanical and electrical connection therewith. The sleeves 19 and 19^a are welded to the spring 17 and the member 13 respectively. A spiral grid 20 is arranged coaxial with the cathode 18 and has its upper and lower ends arranged parallel to the axis of the spiral. The upper end is sealed in the rod 16 and the lower end is joined to the member 14. A substantially cylindrical anode 21 supported by the member 15 envelopes the cathode and anode. An insulating member 22 similar to 16 is provided just below the electrode assembly and serves to maintain the metallic members 12, 13, 14 and 15 in 85 their spaced relation.

In the particular form of electron discharge device to which this invention is most applicable, the cathode is a filament of hair-like dimensions and is for that reason 90 difficult to work with in the assembling of the device. The arrangement of the sleeves 19 and 19^a on the ends thereof materially assists in the assembling since the weight of the sleeve 19^a holds the filament vertical 95 when the sleeve 19 is grasped, and it is thus possible to easily place the filament within the grid 18 by merely holding the filament above the upper end thereof and dropping it through. Furthermore, when the sleeves 19 and 19^a are welded to the elements 17 and 13 respectively, there is no danger of a thin 100 spot resulting at the welding point. The members 16 and 22 cooperate with the supports and leading-in wires for the various 105 electrodes to maintain them in their spaced relation.

It is, of course, understood that various modifications may be made in this structure without in any way departing from the 110

spirit of the invention as set forth in the appended claims.

What is claimed is:

1. In an electric discharge device, an electrode supporting structure comprising a pair of longitudinal metallic members, lateral insulating members carried by said longitudinal members, a grid electrode supported between said lateral members, an anode carried by one of said longitudinal members and a cathode attached to the other.
2. In an electric discharge device, an electrode supporting structure comprising a pair of longitudinal metallic members, lateral insulating members carried by said longitudinal members, a plurality of electrodes supported by said longitudinal members, each of said longitudinal members serving as a leading-in wire for one of said electrodes.
3. In an electric discharge device, an evacuated vessel, a pair of metallic members sealed in said vessel and extending within said vessel, an insulating member carried by the free ends of said metallic members, an anode supported by one of said metallic members, a cathode supported by the other of said metallic members, said metallic members serving as leading-in wires for said electrodes.
4. In an electric discharge device, an evacuated vessel comprising a press, a plurality of metallic members held in said press, two of said metallic members extending substantially the full length of said vessel and the remainder terminating a short distance from the press, an anode carried by one of said long metallic members, a cathode supported at one end from said other long metallic member and at its other end from a short metallic member, said metallic members acting as leading-in wires for said electrodes, and an insulating connection between the free ends of said long members.
5. In an electric discharge device, an evacuated vessel, a press therein, a plurality of leading-in wires sealed in said press, one of said leading-in wires extending substantially the full length of the vessel and having a flattened portion, a spring welded to said flattened portion and extending at an angle to said leading-in wire, a cathode, and supporting connections between said cathode and said spring and another of said leading-in wires.

In witness whereof, I hereunto subscribe my name this 28th day of December A. D., 1921.

PAUL SCHWERIN.
